(57) **CLAIM**

The ornamental design of an auditorium seat, as shown and described.

DESCRIPTION

FIG. 1 is an isometric view of the auditorium seat incorporating my new design, wherein portions are illustrated in phantom and form no part of the claimed design;
FIG. 2 is a front elevation view thereof;
FIG. 3 is a right side elevation view thereof, the left side elevation view being a mirror image;
FIG. 4 is a top plan view thereof; and,
FIG. 5 is a rear elevation view thereof.
